ARTHUR L. PAYTON, OF CHICAGO, ILLINOIS.

VACUUM FEED DEVICE FOR CARBURETERS.

1,332,855.

Specification of Letters Patent.

Patented Mar. 2, 1920.

Application filed May 18, 1917. Serial No. 169,438.

To all whom it may concern:

Be it known that I, ARTHUR L. PAYTON, a citizen of the United States, residing at Chicago, in the county of Cook and State 5 of Illinois, have invented a certain new and useful Improvement in Vacuum Feed Devices for Carbureters, of which the following is a full, clear, concise, and exact description, reference being had to the accompanying drawings, forming a part of this specification.

My invention relates to vacuum feed devices for carbureters and has for its object the provision of improved means associated 15 with a carbureter and a fuel supply reservoir located below the level of the carbureter and arranged to feed the fuel from the supply reservoir up into the fuel chamber of the carbureter.

It has been the practice in the past in forcing or feeding fuel from the supply reservoir up into the carbureter to provide what is commonly referred to as a vacuum tank which is located above the level of the carbureter and which has communication 20 with both the supply reservoir and the carbureter. The vacuum tank is subjected to some vacuum or pressure reducing means so that a difference of pressure is provided 25 between the vacuum tank and the supply reservoir. Due to the reduction of pressure thus provided in the vacuum tank the fuel is forced from the supply reservoir into the tank and is permitted by gravity to flow 30 downwardly into the carbureter as the carbureter requires the fuel. The vacuum producing means has usually been provided by connecting the vacuum tank with the intake manifold of the engine or with that 35 portion of the carbureter in which the pressure is reduced upon operation of the internal combustion engine with which the carbureter and manifold are associated.

It is one of the objects of the present invention to provide a vacuum feed tank between the fuel supply reservoir and the carbureter, means for causing a reduction of pressure in the tank, and a differential pumping device operated by the reduction 40 of pressure and arranged to pump the fuel from the supply reservoir to the tank. The differential pumping device is provided by utilizing a piston-like member having two different working areas, one greater than 45 the other, the greater area being subjected to the reduced pressure provided by the in-

ternal combustion engine and that portion of the pump forming the lesser area arranged to lift the fuel from the supply reservoir to the tank.

In the preferred form of my invention this differential pumping device is made up in the form of a float so that it not only acts as a pumping member when the tank is in condition to receive fuel from the supply reservoir, but also acts as a means for controlling the passageway extending between the vacuum tank and the intake manifold so that the operation of the differential pump may be discontinued when the fuel 65 in the tank reaches a certain pre-determined level.

These and other improved features of my invention will be pointed out in detail in connection with the accompanying drawings wherein:

Figure 1 is a vertical cross sectional view of the device of my invention;

Fig. 2 is a horizontal cross sectional view taken along the line 2-2 of Fig. 1 looking 70 in the direction indicated by the arrows; and

Fig. 3 is a fragmentary view similar to Fig. 1 showing the differential pump in its uppermost position.

Similar characters of reference refer to similar parts throughout the several views.

In Fig. 1, 4 designates a power cylinder having the internal threads 5 and 6 at the bottom and top thereof respectively. The threads 6 are arranged to coöperate with and hold in place the cap 7 containing an air inlet passageway 8 and the valve seat 9. The passageway 8 communicates with the gooseneck 10 open to the atmosphere. The cap 7 contains an exhaust passageway 11 containing the valve seat 12 and communicating with the conduit 13 which extends to the intake manifold of the engine, or to that portion of the carbureter such as the atomizing chamber in which a vacuum or reduction of pressure is produced upon operation of the engine. Extending upwardly into the passageway 8 and arranged to coöperate with the inlet valve seat 9 is the valve 14 pivoted at 15 to a lever 16. The valve lever 16 is in turn pivoted at 17 to a stud 18 extending downwardly from the cap 7. Arranged to coöperate with the valve seat 12 and to extend into the passageway 11 is an 110 exhaust valve member 19 pivoted at 20 to the lever 16. Mounted for oscillation upon

the pivot pin 17 is a float lever 21 extending to the axis of the cylinder 4 and pivotally connected at 22 to a downwardly extending rod 23 having the head 24. The pin 22 and the pin 20 are connected by the coiled tension spring 43, the function of the spring being to operate the valves 14 and 19 quickly when such action is to take place.

As most clearly shown in Fig. 1 the lower end of the rod 23 has lost motion connection with the differential pump device 25, consisting of a float member 26 and the pump member 27. The float member 26 is made slightly smaller than the inside diameter of the cylinder 4 so as to provide the space 27' between the float and cylinder into which oil or fuel may pass to seal the upper side of the float 26 from the lower side. The piston member 27 consists of a cylindrical cup shaped member 28 having a cap 29 secured thereto in any suitable manner. The cap is provided with a number of openings shown at 30—30 in Figs. 1 and 2. Attached to the central portion of the piston 27 is an upwardly extending rod 31 having a hook 32 extending through a downwardly projecting hook 33 provided on the underside of the float 26. The purpose of the connection 32 and 33 is to connect the float 26 and piston 27 so that they operate or move vertically in unison, but so that they may have slight relative lateral movement. The lower end of the piston 27 carries the downwardly seating valve member 34. The entire piston member 27 is arranged to reciprocate within the pump cylinder 35 attached to the base 36 having threading engagement with the threads 5 of the cylinder 4, as illustrated. The inside of the cylinder 35 communicates with the passageway 37 having a downwardly seating fuel inlet check valve 38 therein and communicating with the conduit 39 extending downwardly to and communicating with the interior of the fuel supply reservoir. The cap 26 is also provided with the passageway 40 communicating with the inside of the cylinder 4 at a point outside of the cylinder 35 and containing an upwardly seating fuel outlet check valve 41. The passageway 40 is connected with the fuel chamber of the carburetor by the conduit shown at 42. The interior of the cylinder 4 and that portion of the cylinder located below the float 26 communicates with the atmosphere through the pipe 43.

The operation of the device is as follows: Assuming the parts to be in the position shown in Fig. 1 and that the engine whose intake manifold is connected with the conduit 13 is operating a vacuum or reduction of pressure is produced in the vacuum chamber shown at A between the top of the float 26 and the cap 7. Due to the vacuum or reduction of pressure thus provided in this chamber the entire differential pump mecha-

nism including the float 26 and the piston 21 will move upwardly thus causing a reduction of pressure in the suction chamber shown at B which results in a flow of fuel from the supply reservoir upwardly through the conduit 39, past the check valve 38, and into the chamber B. After the differential pump mechanism has moved upwardly a certain distance the head 24 of the rod 23 is engaged by the float 26 and the lever 21 moved upwardly about its pivot 17. When the lever 21 has been moved upwardly a distance sufficient to bring the pin 22 above the pivot pin 17 so that the center line of the spring 43 assumes a position above the pin 17 the lever 16 will be oscillated in a clockwise direction (Fig. 1) so that the valve 19 co-operates with the seat 12 and the valve 14 moves downwardly to provide communication between the chamber A and the atmosphere. The last mentioned operation of the valves 14 and 19 thereby produces atmospheric pressure in the chamber A so that gravity is permitted to lower the differential pump mechanism and the pump mechanism will be so lowered unless the supply chamber C contains a quantity of fuel which prevents such lowering of the pump mechanism. As the pump mechanism lowers the fuel in chamber B passes upwardly through the check valve 34 into the cylinder 28. When the differential pump mechanism has been lowered to the position shown in Fig. 1 the spring 43 is moved below the pin 17 so as to oscillate the lever 16 and again provide communication between the chamber A and the intake manifold of the engine and prevent communication between the chamber A and the atmosphere. The operation above described is then repeated.

After the fuel is taken into the pump piston 28 it is passed over the top of the cylinder 35 into the chamber C from which it is allowed to pass by gravity downwardly into the fuel chamber of the carburetor. When the chamber C contains a sufficient amount of fuel the float 26 and thus the entire differential pump mechanism is not permitted to move downwardly and thus provide communication between the chamber A and the intake manifold of the engine until enough fuel from the chamber C has been taken in by the carburetor through the conduit 42 to permit such downward movement, whereupon the chamber C is again filled and the pump mechanism held idle until the carburetor again takes a sufficient amount to lower the float 26 to a position where the valve 19 is again opened.

In Fig. 3 I have shown the float 26 in its uppermost position and the valves 19 and 14 closed and open respectively.

Having thus described my invention what I claim as new and desire to secure by Letters Patent of the United States is:

1. In a vacuum fuel feed tank the combination of a pair of differential cylinders, the larger cylinder forming a power cylinder and the smaller a pumping cylinder, differential pumping mechanism reciprocably mounted in the cylinders, said mechanism comprising a float disposed within the power cylinder and a piston member attached to the float and disposed in the pump cylinder, a suction conduit communicating with the power cylinder, and valve mechanism controlled by the float for regulating communication between the suction conduit and the power cylinder.
2. In a vacuum fuel feed tank the combination of a pair of differential cylinders, the larger cylinder forming a power cylinder and the smaller a pumping cylinder, the upper end of the pump cylinder communicating with the power cylinder, differential pump mechanism reciprocably mounted within the cylinders, said mechanism comprising a float disposed in the power cylinder and a piston member attached thereto and disposed in the pump cylinder, a fuel inlet at the lower end of the pump cylinder, a fuel outlet at the lower end of the power cylinder, a suction conduit at the upper end of the power cylinder, and valve mechanism controlled by the float for regulating communication between the suction conduit and the power cylinder.
3. In a vacuum fuel feed tank the combination of a pair of differential cylinders, the larger cylinder forming a power cylinder and the smaller a pumping cylinder, the upper end of the pump cylinder communicating with the power cylinder, differential pump mechanism reciprocably mounted within the cylinders, said mechanism comprising a float piston disposed in the power cylinder and a piston member attached thereto and disposed in the pump cylinder, a downwardly seating check valve in the piston member, a fuel inlet at the lower end of the pump cylinder, a fuel outlet at the lower end of the power cylinder, a suction conduit at the upper end of the power cylinder, an air vent at the upper end of the power cylinder, valve mechanism controlled by the float piston for regulating communication between the power cylinder and the suction conduit and air vent, and an air vent for the power cylinder below the float piston therein.
4. The combination with communicating power and pump cylinders, of differential pumping means located in said cylinders comprising a member located in said power cylinder, a piston member located in said pump cylinder and actuated by said first-named member, means for establishing communication between said power cylinder and
- a source of suction, and means actuated by said first-named member for connecting said power cylinder with and disconnecting it from said source of suction.
5. The combination with communicating power and pump cylinders, of pumping means located in said cylinders comprising a member located in said power cylinder, a piston member located in said pump cylinder and actuated by said first-named member, means for establishing communication between said power cylinder and a source of suction, and means actuated by said first-named member for connecting said power cylinder with and disconnecting it from said source of suction.
6. The combination with a power cylinder, of a pumping means comprising a pump cylinder communicating with said power cylinder, a piston member in said pump cylinder, means in said power cylinder for actuating said piston member, said actuating means being controlled by the level of the liquid in said power cylinder delivered thereto by said pumping means.
7. The combination with a storage chamber, of means for establishing communication between said storage chamber and a carburetor, and means for pumping fuel from a level below the level of said storage chamber and delivering it to said storage chamber, comprising a combined float and piston member controlled by the level of the fuel in said storage receptacle.
8. The combination with communicating power and pump cylinders of differential pumping means for said cylinders comprising a member located in said power cylinder, a movable wall for said pump cylinder and actuated by said member, means for establishing communication between said power cylinder and a source of suction and means actuated by said member for connecting said power cylinder with and disconnecting it from said source of suction.
9. The combination with communicating power and pump cylinders of differential pumping means for said cylinders comprising a member located in said power cylinder, a movable wall for said pump cylinder and actuated by said member, means for establishing communication between said power cylinder and a source of suction and means for connecting said power cylinder with and disconnecting it from said source of suction.
- In witness whereof I hereunto subscribe my name this 12th day of May, A. D. 1917.
